UNITED STATES PATENT OFFICE.

PHILIP S. HARPER, OF CHICAGO, ILLINOIS.

GAS BURNER.

Application filed January 26, 1921. Serial No. 439,905.

My invention relates to a gas burner and particularly to a gas burner of the type in household use for cooking purposes.

The primary object of my invention is a gas burner which will provide the advantageous quick heating of the largest burner and automatically at the same time provide the efficiency of the smallest burner when reduced heat is required.

10 It has been determined by experiment that a vast amount of heat is lost when the flame from a gas burner is out of contact with the bottom of the cooling vessel and this is particularly true when the ordinary gas 15 burner is turned low and the flame extends but a very short distance above the gas burner. In such instances it would be more advantageous to shut off the flow of gas from a portion of the gas burner and allow 20 a portion of the burner to remain burning at full force.

To accomplish this I have devised a burner divided into sections, each section having an individual tube where gas to a particular 25 section is brought into mixture with air; and I have devised a common control means for admitting a supply of gas to some or all of the mixing tubes as the conditions require so that one or more sections of the 30 burner can be cut off without disturbing the burning in the remaining sections.

I am aware that burners of this type have been devised wherein any number of sections may be burned by manipulation of a 35 common cock, but in my burner I claim a particular arrangement of parts so as to make a burner of this type adapted to the space available on the usual gas range, a burner having a very much smaller and less 40 expensive cock than heretofore employed, and a burner of such simplified arrangement as to be more easy of manufacture and more reliable in operation.

Another object of my invention is the 45 provision of a sectional gas burner having a common means of control for all of the sections so arranged that the force of the burner can be reduced in certain sections while allowing other sections of the burner 50 to burn with full force. For instance, the outside section of the burner can be turned down while the intermediate and center sections are allowed to remain at full force and a slightly greater turn of the control valve 55 will completely shut off the outside section and still not affect the flame of the inner

sections. By further closing the control valve, the flame of the intermediate section will be turned lower, the center section remaining at full force and so on until we 60 have only the center section burning which may also be turned down for a minimum supply of heat. It will thus be understood that by varying the condition of the control valve any degree of heat regulation may be 65 obtained.

These and other objects of my invention will be more fully and better understood by reference to the accompanying sheets of drawings, in which—

70 Figure 1 is a partial sectional plan view of a three-section burner taken along line I—I of Figure 2;

Figure 2 is a vertical sectional view taken on line II—II of Figure 1;

Figure 3 is a vertical sectional view taken on the line III—III of Figure 2; and

Figure 4 is a longitudinal sectional view of a two-section gas burner as distinguished from a three-section burner as shown in 80 Figures 1, 2 and 3.

Referring now specifically to the drawings, a gas supply pipe 10 is shown to which a valve casing 11 is secured in any approved manner, the valve casing 11 having a valve 85 member 12 extending therethrough, which has a threaded nut 13 on the lower end thereof, with a spring 14 interposed between the nut 13 and a washer 15 which bears against the valve casing 11 and provides means for 90 holding valve member 12 in proper position, yet allowing the said valve member 12 to be turned for the admission of gas as herein-after described. Extending longitudinally of the valve casing 11 and spaced apart from 95 each other is a plurality of passages 16, 17 and 18 which vary in size for a purpose to be disclosed. Extending transversely through the valve member 12 is a plurality of passages 19, 20 and 21, the said passages corresponding 100 in size to the passages 16, 17 and 18 respectively, that is, the passage 19 is the same size as the passage 18, the passage 20 is the same size as the passage 17, and the passage 21 is the same size as the passage 16. The passages 16, 17 and 18 in the valve casing 11 extend on

105 the opposite side of the valve member 12 from the gas supply pipe 10 and connect with enlarged passages 22, 23, and 24, the connection in each case being closed by an 110 adjusting screw 25 by which various degrees of opening may be obtained between passages

16, 17 and 18 and respective enlarged passages 22, 23 and 24. These enlarged passages 22, 23 and 24 lead in respective order to a plurality of gas nozzles 27, 28, and 29 in which are passages 30, 31, and 32 in connection with respective restricted openings 33, 34, and 35. The gas nozzles 27, 28, and 29 project through a sliding air shield 44 and into the burner body 36 in such a manner that restricted openings 33, 34, and 35 discharge into mixing tubes 40, 41, and 42, each to its respective tube, the said mixing tubes 40, 41 and 42 are placed one above the other in a common casing, and said tubes in 15 the form of the invention shown are in a common vertical plane with the gas nozzles 27, 28 and 29. Of the said mixing tubes 40, 41, and 42, each has openings 9 to the outside air the area of which openings may be adjusted by loosening the screws 43 and moving air shield 44 to or from the burner 36 as the case may be. The burner body 36 is divided into a plurality of sections 37, 38, and 39 which connect respectively to before- 20 mentioned mixing tubes 40, 41 and 42. Each section 37, 38, and 39 has a number of the usual openings 26 through which the combustible mixture passes and burns from the top of burner body 36 in the usual manner. 25 It will be noted that section 37 extends around the outer edge of burner body 36 and is initially supplied with gas through the passage 16 in valve casing 11; in like manner section 38 is supplied by passage 17 and section 39 by passage 18. It will also be noted that the passage 16 is smaller in size than either of the other passages 17 and 18 so that as the member 12 is turned the passage 16 is closed before either of the other passages 17, and 18 are closed. Consequently 30 gas will pass to sections 38 and 39 with section 37 closed off and for the same reason gas will still pass to section 39 after the closing off of sections 37 and 38. Now the 35 passages 16, 17 and 18 are sufficiently different in size, each from the remaining, and sufficiently large in size as compared with other areas through which the gas must pass that gas supply to any section is not appreciably 40 diminished on the turning of the valve member 12 until the next section situated outside from the one in question is entirely cut off. This result is more easily accomplished in the design since section 38 is smaller in size 45 than the section 37 and requires less gas for a full height flame, consequently the partial opening of its larger supply port 17 may easily be made proportionate to its required amount of gas; and in the case of the smallest section 39 being supplied by the largest port 18, it is evident that only a very small opening of this port is required to supply this smallest section with its normal full gas supply. It will be seen that as the valve member 12 is turned toward the closing posi-

tion there results in progressive order a gradual closing off of outermost section burning while any sections interior to the section affected will be burning at full force.

As to the operation of this burner, it is necessary to make a permanent adjustment of air shield 44 to give a proper combustion mixture with the quality of gas being supplied and with valve member 12 in full open position to make a similar adjustment of screws 25 to give the desired full height flame on the normal gas pressure employed before the burner. Then on the regular operation it is only necessary to control the burning by the turning of the valve member 12 in the customary manner. By inspection of the flames, as is customary in any gas burner when turning the gas lever downward, an operator in entirely cutting off one section may turn the lever just so far as to very slightly lower the flames of the next innermost section, and in this way make certain that the section being cut off is entirely cut off and that there is no small amount of gas still escaping.

In Figure 4 I have illustrated a modified form of my invention and in which a burner body 45 is shown having two sections 46 and 47, the section 47 extending circumferentially around the outer portion of the burner body 45 and being supplied with gas in much the same manner as the burner shown in Figures 1, 2 and 3 and previously described. A gas supply pipe 48 is provided having a valve casing 49 secured thereto through which a valve member 50 extends. The said valve casing 49 has a plurality of passages 51 and 52 extending longitudinally therethrough, the passage 51 in its vertical downward continuation being intercepted by permanent adjusting screw 53 for permanently adjusting the maximum gas supply to the central section 46 of the burner. It will be noted that in this form of my invention I have omitted a permanent adjusting screw for the gas to the outer section 47 as the height of maximum flame from this section could be regulated by the valve member 50 or this part of the burner could be equipped with an adjustable nozzle in accordance with present practice. Passages 54 and 55 extend through the valve member 50 and are the same size as the passages 51 and 52 respectively. Gas nozzles 56 and 57 are secured to the member 49 and have passages 58 and 59 respectively therein with restricted communicating passages 60 and 61 which discharge into the mixing tubes 62 and 63 placed one above the other in the burner body 45. An opening 64 is provided through which air is admitted to the mixing tube 62 and on which in this instance no adjustment is supplied as is often customary in small burners. The usual rotating member 67 and stationary member 65 are supplied for adjusting air

supply to large mixing tube 63. It will be understood that by turning the member 50 in this form of my invention that the passage 52 is closed prior to the closure of the passage 51 and thereby the flame through the outside section 47 of the burner can be turned down or controlled in any manner while section 46 is burning at full capacity. By further turning of the valve member 50 10 the gas is completely shut off from the mixing tube 63 which leads to the outer section 47 of the burner and thus completely shuts off this section while allowing the center section 46 to continue in full operation or be 15 reduced as required.

It can be seen from the foregoing that I have devised a fuel burner which has all the combined advantages of a plurality of burners of different sizes and, as well, have incorporated other advantages which will be apparent without further description.

While I have described more or less precisely the details of construction, I do not wish to be understood as limiting myself thereto, as I contemplate changes in form 25 and the proportion of parts and the substitution of equivalents as circumstances may suggest or render expedient without departing from the spirit or scope of my invention.

30 I claim:

1. In a gas burner, a burner body member having a plurality of heating sections, said sections being arranged within the area covered by the usual cooking vessel, and having a plurality of burner ports in the upper side of each of said burner sections, a plurality of mixing tubes connecting directly into said sections, each tube to its respective section, each of the said mixing tubes being 40 positioned one above the other, and each tube separated from another by a substantially horizontal wall; a valve casing having a plurality of passages therein leading to the said mixing tubes; and control means 45 in the said valve casing.

2. In a gas burner, a burner body member having a plurality of heating sections, said sections being arranged within the area covered by the usual cooking vessel, and having 50 a plurality of burner ports in the upper side of each of the said burner sections, a plurality of mixing tubes connecting directly into the said sections, each tube to its respective section, the said mixing tubes comprising 55 passages in a common casing, each of the said mixing tubes being positioned one above the other, and each tube separated from another by a substantially horizontal wall, a valve casing having a plurality of passages 60 therein leading to the said mixing tubes, and control means in the said valve casing.

3. In a gas burner, a burner body member having a plurality of heating sections, said sections being arranged within the area covered by the usual cooking vessel, and having

a plurality of burner ports in the upper side of each of said burner sections, a plurality of mixing tubes connecting directly into said sections, each tube to its respective section, each of the said mixing tubes being positioned 70 in a common casing one above the other, and each tube separated from another by a substantially horizontal wall, a valve casing having a plurality of passages therein leading to the said mixing tubes, and a 75 rotatable valve member so arranged in said casing as to intercept said passages at different points along the axis of the said rotatable valve member.

4. A gas burner comprising a plurality 80 of heating sections, said sections being arranged within the area covered by the usual cooking vessel, and having a plurality of burner ports in the upper side of each of the said burner sections, a plurality of mixing tubes connecting directly into said sections, each tube to its respective section, each 85 of the said mixing tubes being positioned in a common casing one above the other, and each tube separated from another by a substantially horizontal wall, a valve casing having a plurality of passages therein leading to the said mixing tubes, said 90 passages being positioned in a common vertical plane, and control means in the said valve casing.

5. A gas burner having a plurality of burner sections and a plurality of mixing tubes equal to the number of said burner sections, a gas supply pipe, a valve casing 100 having a plurality of passages having different diameters, a rotatable valve member having transversely extending passages therethrough corresponding in size and number to the passages in said valve casing 105 and positioned in the same vertical plane, whereby when the valve member is turned some of the said passages are open while others are closed.

6. In a gas burner, a burner body member 110 having a plurality of heating sections, said sections being arranged within the area covered by the usual cooking vessel, and having a plurality of burner ports in the upper side of each of the said burner sections, a plurality of mixing tubes connecting directly into the said sections, each tube to its respective section, a valve casing having gas supply passages therethrough leading to the said mixing tubes, a rotatable 115 plug in the said casing having passages corresponding in size to passages in the said casing, said passages differing in diameter whereby on rotation of the said plug the smaller passages close before the larger. 120

7. In a gas burner, a burner body member 125 having a plurality of heating sections, said sections being arranged within the area covered by the usual cooking vessel, one of said sections being larger than one of the 130

others, said body member having a plurality of burner ports in the upper side of each of said burner sections, a plurality of mixing tubes connecting directly into the said sections, each tube to its respective section, a valve casing having gas supply passages therethrough leading to said burner sections by way of said mixing tubes, a rotatable plug in the said casing having passages corre-

sponding in size to passages in the said casing, said passages differing in diameter whereby on rotation of the said plug the smaller passages close before the larger, a smaller one of said passages leading to a larger one of said burner sections. 10

Signed at Chicago, Illinois, this 18th day of January, 1921. 15

PHILIP S. HARPER.
